UNITED STATES PATENT OFFICE.

EDWARD H. ELLISON, OF JAMESTOWN, NEW YORK, ASSIGNOR TO ELLISON BRONZE COMPANY, INC., OF JAMESTOWN, NEW YORK, A CORPORATION OF NEW YORK.

AUTOMOBILE RADIATOR CAP.

Application filed December 19, 1923. Serial No. 681,503.

To all whom it may concern:

Be it known that I, EDWARD H. ELLISON, a citizen of the United States, residing at Jamestown, in the county of Chautauqua, State of New York, have invented certain new and useful Improvements in Automobile Radiator Caps, of which the following is a description, reference being had to the accompanying drawing and to the figures of reference marked thereon.

This invention relates to automobile radiator caps, and more particularly to a cap adapted to support a motometer or, in lieu thereof, an ornamental figure.

One of the main objects of the invention resides in providing an ornamental cap for automobile radiator filling nozzles which is composed of one or more interchangeable parts whereby, with the substitution of a single part, the cap is adapted for use with any standard make of automobile, and also with the substitution of a variety of shapes of another part, the cap as a whole, can be altered in general ornamental appearance so as to provide a variety of styles of cap for any single make of car or a distinctive cap for each automobile manufacturer.

Still another object of this invention resides in providing an ornamental cap proper having a standard size threaded opening whereby it may be coupled to the filling nozzle of the radiator and in providing interchangeable adapters or sleeves, each of which has a thread corresponding to the standard thread of the cap proper and each of which has a thread corresponding to the thread of the filling nozzle of the predetermined automobile.

The particular feature of this invention in so far as the adapter is concerned, relates to the integrally cast lugs on the adapter whereby it may be easily positioned on the water filling spout of the motor vehicle.

Yet another feature of the invention relates to the specific construction of the threaded surfaces of the adapter and particularly to the means for locking the adapter to the filling spout and the cap proper to the adapter to prevent theft.

Yet a further feature of the invention relates to the construction of the cap proper with particular reference to the improved manner of mounting the hinged cover and the manner of clamping it in place whereby to compensate for wear and variation in

gasket thickness and also to insure a uniform seating of the cover on the gasket.

Still another object of the invention resides in the arrangement of the bail for clamping down the hinged cover on its gasket seat whereby the bail not only provides a most effective uniform clamping pressure about the entire circumference of the gasket; enables the mounting of the motometer centrally of the cap, but also permits the bail to swing out of the way so that the hinged cover can be swung open freely.

A further object in the particular construction of the bail resides in preserving its symmetrical ornamental shape while at the same time arranging it for a swinging movement clear of the hinged cover.

Yet another object of the invention lies in the means for tightly clamping the bail down on the hinged cover, which means is effective irrespective of the substitution of one ornamental shape of bail for another when necessary to change the type of cap for a particular manufacturer.

Another feature of the bail clamping means resides in the construction for preventing felonious removal of the bail.

These and other objects will be apparent from a perusal of the following specification when taken in connection with the accompanying drawings, wherein—

Figure 1 is a front view of an automobile radiator provided with my improved cap shown in assembled position on the water spout of the radiator;

Fig. 2 is a plan view of the cap without the motometer;

Fig. 3 is a side view of the cap, the latter being shown in section;

Fig. 4 is a section on the line 4—4 of Fig. 3;

Fig. 5 is a plan view of the adapter showing the integral lugs by which means the adapter is rotated;

Fig. 6 is a detail of part of the cap;

Fig. 7 is a sectional detail view of the pivotal connection for the bail, and

Fig. 8 is a similar view showing a modification.

Referring now to the drawings in detail, the radiator 1 is provided with the usual water spout 2, which in the form shown, is provided with an exterior thread of desired pitch. This threaded radiator water spout

is adapted to receive the automobile radiator cap forming the subject-matter of the present invention. The cap comprises a body portion or cap proper 3, substantially of 5 open-ended sleeve-like formation, the open top of which is adapted to be closed by a cover hereinafter described. The bottom of the cover proper 3 has an opening of 10 standard diameter, which is interiorly threaded as at 4.

In order to permit this standard body portion 3 to be coupled to the variant sized water spouts of the different makes of automobiles, interchangeable adapters or sleeves 15 are provided, which sleeves are relatively cheap to manufacture in comparison with the cost of preparing separate body portions 3 for each type and size of automobile spout. These adapters 5 are provided with an outer 20 diameter of a size corresponding to the inner threaded diameter 4 of the cap proper 3, and with a lower threaded portion 6 of a diameter corresponding in size to the diameter of the filling spout of the particular automobile 25 to which the cap is to be attached. Thus, by providing a plurality of adapters, each of which has a standard upper threaded portion to connect to the standard lower opening of the body portion 3, and each of 30 which has its predetermined threaded opening to fit the selected automobile, great economy in manufacturing costs can be effected. In the specific details of construction, the adapter 5 is provided above the inner screw 35 thread 6 with a recess 7 in which is seated a gasket 8. This gasket abuts an overhanging ledge 9 so that when the adapter is screwed upon the filling spout, the upper end of the spout will firmly press the gasket 40 against the ledge and make a water-tight connection.

It will be obvious that the adapter can be provided with a threaded portion on its lower exterior surface to engage with a corresponding thread on the inner wall of the filling spout, the same being more or less a reversal and arrangement of parts. The upper surface of the overhanging ledge 9 is provided at substantially diametrical points 50 with two upstanding lugs 10 and 11 which are preferably cast with the adapter 5. As illustrated clearly in Fig. 5, these lugs are disposed so that a rigid rod can be inserted therebetween so that the adapter can be secured tightly upon the filling spout. It is 55 obvious that other arrangements of these lugs is contemplated.

In order to prevent felonious removal of the adapter from the filling spout, the lower 60 wall of the adapter is provided with a bore 12 extending clear through the same, in which bore a threaded screw 13 is disposed, which screw is provided with an inset recess 65 for the reception of an angularly shaped turning wrench 14. This coupling of the

adapter to the filling nozzle may be made permanent by mashing a small lead shot into the recess of the screw 13 so that it cannot be turned by any instrument. In a similar manner, there is provided means for permanently locking the adapter to the cap proper 70 3, and this comprises a radial bore 15 projecting through the upper wall of the adapter 5. In the form illustrated, this bore is drilled through the upstanding lug 10 and is threaded to receive a locking screw 16 having an inner recess to receive the angular turned end of the wrench 14. In a like manner, a lead shot is inserted in the recess of 75 this screw 16 and machined, so that the screw 80 cannot be moved.

Above the inner thread 4 on the lower portion of the cap proper 3 is a recess in which seats a packing 17 which abuts an overhanging ledge 18, thereby forming a 85 firm seat on the water-tight connection when the adapter and cap proper 3 are secured tightly together.

The upper open end of the cap proper 3 is provided with an annular inwardly projecting seat 18' having a concentric recess adapted to seat a gasket 19. This open upper end of the cap body is adapted to be closed by a cover 20 which not only forms a water and steam-tight cover for the radiator spout, but also forms a support for the usual motometer or other ornamental device carried by the cap. This cap is provided with an improved means for clamping it firmly upon the gasket 19, with substantially uniform pressure around the entire circumference of the gasket, which means is additionally constructed to permit the motometer or other ornament to be mounted centrally of the cover 20. In addition, the 90 novel construction permits the cover clamping means to be swung clear of the usual hinged connection between the cover 20 and the body 3, so that the cap of cover 20 may be swung fully open when it is desired to fill 95 the radiator. In the present embodiment, the cap 20 is shown with a hinged connection 21 preferably located directly at the rear of the body 3. For the purpose of compensating for irregularities in the thickness 100 of the gasket 19, due to wear and defects in manufacture, the hinge is provided with an elongated slot 22 so that the cover can adjust itself to these conditions. In order to 105 provide the necessary downward pressure of the cover on the gasket, there is provided a bail 23 which is arranged to press down upon the cover on substantially opposite sides of a line passing diametrically through the cover, so that the pressure will be applied at two points through the center line 110 of the cover. In this way, a uniform downward distribution of the pressure is provided. The bail 23 is pivoted to the 115 diametrically opposite sides of the body 3, and 120 125 130

to this end, the body is formed with outstanding lugs 24 and 25, which lugs form housings for the pivotal mounting of the bail. As illustrated clearly in Fig. 7, each 5 one of these lugs is provided with a vertically arranged recess 26 adapted to house a plunger 27 which has a vertical sliding motion in the recess 26. This plunger is formed with portions of two diameters, a 10 lower larger diametrical portion and an upper stem 28 of smaller diameter. The stem 28 has coiled therearound a spring 29 which operates to normally press the plunger 27 downwardly. The stem 28 not only acts as 15 a guide to hold plunger 27 in vertical position, but it also serves to prevent damage to the spring, when the thread on 30 is being mutilated, as in Fig. 7, or when the indentation 27" is being driven in, as in Fig. 20 8. When plunger 27 is pushed up as far as it will go, the stem will then touch the roof of the hole in housing 24. The stem will then take the impact when the bolster 27" is being hammered in. The top of stem 25 will touch the roof, before 30' will touch the top of elongated hole 31. The lower larger diameter of the plunger 27 is provided with a cross bore which is internally threaded to receive a pin 30 provided on its 30 inner end with a corresponding threaded portion. The outer portion of this pin projects through a slot 31 in the outer wall of the lug 25. On the outer end of the pin 30 is pivotally mounted the lower arm or bail 35 23, which lower arm is provided with a downwardly projecting flange 32 suitably bored to receive this pin 30. The bottom of the plunger 27 is likewise provided with a bore 27' therethrough, which permits the 40 mutilation of the threads of the pin 30 to prevent the removal of the bail from the body.

As an alternative form of this construction, that of Fig. 8 is illustrated. In this 45 form, the pin 30 is not threaded at its inner end but is provided with a groove 30', and furthermore, the plunger 27 is not bored, but is adapted to be struck inwardly as at 27" so that the pin cannot be withdrawn after it is once assembled.

Obviously, the opposite pivotal connection 50 is similarly constructed. The upper portion of the bail 23 preferably extends laterally on each side of the body portion 3 to provide symmetrically shaped wings, the upper portions of which fold or extend inwardly on a line passing centrally through the middle of the cap, substantially to a point 55 33 on each side thereof, at which point the extension then curves backwardly and concentrically around the cap as at the point 34 (see Figures 2 and 3). The upper surface of the cap proper 3 at substantially opposite points in line with the extensions 60 35 of the bail is provided with upstanding lugs

36, which lugs are integral with the cap. These lugs are preferably provided at their forward ends with upstanding nibs 37 which have rearwardly sloping surfaces 38, so that when the bail is swung about its pivotal 70 points 30, the extensions 35 will ride up the inclined surfaces 38 and will abut against the upstanding nibs 37 to limit the further forward movement of the bail relatively to the cap. As the bail is thus swung upwardly, the inclined surfaces 38 will pull on the lower pivotal portions of the bail 23, thus pulling the pivot pins 30 upwardly in their slots 31 and putting the springs 26 under 75 compression. This constitutes a very effective means for resiliently holding the bail in clamping position against the cap and in addition, a very powerful means for creating a watertight clamping pressure of the cover 80 20 against the gasket 19. It will be manifest from a comparison of views 2 and 3 that when the bail 23 is swung rearwardly, the springs will permit the bail to pivot about the pins 30 and swing so that the curved portion 35 is entirely clear of the hinged connections 21, so that the cap 20 can then be thrown open to full position and will not be interfered with by the bail. From an inspection of Fig. 1, it is evident that by the 85 arrangement above described, the distance between the pivotal pin 30 for the bail and the lower portion of the extension 35 is made at a minimum. This permits the bail to swing free of the hinged cover, and at the same time, permits the use of a bail that does not project upwardly too high, which 90 would not be consonant with good design. In order to make this clear, for instance, if the extension 35 of the bail extended straight across the center of the cap and did not 95 curve back as at the portion 34, it would be necessary to greatly increase the distance between the pivotal pin 30 and the extension 35 to thus permit the bail to swing 100 sufficiently out of the way to permit the cover to be opened. It will also be evident that by means of the spring connection 29, it 105 is not necessary to depend upon the inclined surfaces 38 of the lugs 36 to wedge the cover tightly against its gasket, since in 110 interchangeable bails, where, for instance, an automobile manufacturer desires to have a different shaped bail, the clamping action 115 might be seriously impaired due to slight difference in distance between the pivotal pin 30 and the lower portion of the extension 35.

It will be obvious that a device as above constructed, possesses many advantages from the standpoint of cheapness in manufacture, and also in economy of use, since by substituting the interchangeable adapters 5 for each different size of water spout of a particular automobile made, the cap may be 120 used without further alteration of the stand- 125 130

- ard type of cap. Also by providing bails of variant shapes and design, each of which includes as an essential functional element, the pivotal pin construction and the upper bail extension 35 adapted to cooperate with the lugs 36 on the cap, great economy in manufacture and cost can be made, since the remaining outline of features of the bail can be altered to suit the taste of the particular manufacturer, provided, however, the concentrically circular portion 34 of the bail is incorporated so that the bail can swing rearwardly out of the way of the hinge connection 21 of the cap.
- 15 It is obvious that minor changes in the details of construction and arrangement of the parts may be made without departing from the spirit of the invention as set forth in the appended claims.
- 20 Having thus described the invention, what I claim as new and desire to secure by Letters-Patent, is—
1. A device of the class described comprising an open-top cap body adapted for connection to the filling spout of an automobile radiator, a cover for said cap provided with a central bore for the reception of the sleeve of an upstanding motometer or the like, a hinge connection between said cap body and cover, and a bail pivoted to said cap body and provided with an extension adapted to engage diametrically opposite portions of said cap, said bail and extension being constructed and arranged to permit said bail 25 to swing clear of the top whereby to permit unrestricted opening of said cap.
  2. A device of the class described comprising a cap body adapted to be connected to the filling spout of an automobile radiator and having an open top provided with a concentric gasket seat, a cap having hinged connection at the rear of said body, a bail pivotally connected to the lower opposite portions of said body and having upward 30 extensions extending inwardly to engage upstanding lugs on said cap located in the plane of said bail pivot, said extension comprising an intermediate portion bowed outwardly substantially in the plane of the cap hinge whereby said bail can swing clear of the cap to permit it unrestricted opening.
  3. A device of the class described comprising a cap body adapted for connection with the filling spout of an automobile radiator and formed with an open top provided with a concentric gasket seat, a cap hinged to the rear of said body and provided with upstanding lugs arranged on opposite sides of a line passing centrally through said cap 35 and at right angles to a line passing centrally through said cap and center of said hinge, a bail pivoted to the lower portion of said body on opposite sides thereof and in line with said lugs, said lugs having rearwardly inclined surfaces adapted to engage

said bail extensions when said bail is swung into locking position whereby said cap is forced on to said gasket seat.

4. A device of the class described comprising a cap body adapted to be connected to the filling spout of an automobile radiator, said body having an open top concentrically surrounded by a plane surface having a gasket seat therein, a cap hinged to the rear portion of said body, a bail pivotally connected to said body on opposite sides thereof and adapted to swing over said cap to engage opposite sides thereof, said pivotal connection between the bail and the body being constructed and arranged to shift vertically upon the clamping movement of said bail.

5. A device of the class described comprising a cap body adapted for attachment to the filling spout of an automobile radiator, said body having an open top, a cap hinged to said top, bail housings on opposite sides of said body, a vertically movable plunger arranged in each housing, a spring in said housing adapted to normally force said plunger downwardly, a pin carried by said plunger and projecting through the elongated slot in said housing, a bail ear pivotally carried by each pin, said bail being constructed and arranged to swing over said cap and to engage opposite sides thereof to press said cap firmly into closing position.

6. A device of the class described comprising a cap body adapted for attachment to the filling spout of an automobile radiator comprising an open top, a cap hinged to said top, housings on opposite sides of said body, a vertically shiftable plunger arranged in each housing, a spring confined in said housing, and adapted to force said plunger normally downwardly, a pin carried by each plunger projecting outwardly through the elongated slot in said housing, means for preventing the removal of said pin from said plunger, a bail having portions pivotally mounted on each of said pins, said bail being constructed and arranged to swing over the top of said cap and to engage the opposite sides thereof to clamp the same to said body.

7. A device of the class described comprising a cap body adapted for attachment to the filling spout of an automobile radiator cap, and provided with an open top and a concentrically surrounding gasket seat, a cap hinged to the rear rim of said body and provided with a central aperture for the reception of the stem of a motometer or like ornament, bail housings arranged on opposite sides of the body and provided with outwardly projecting pins, a bail having downwardly extending portions pivotally mounted on said pins and having an upper portion extending over said cap and adapted to engage opposite sides thereof to exert

115

120

125

130

downward pressure uniformly about the circumference of said gasket, said bail having a rearwardly bowed or curved portion extending substantially in a curved plane in line with the hinged connection whereby said bail may be swung clear of said hinged connection so that said cover may open to its fullest extent and free of said bail.

8. A device of the class described comprising a cap body adapted for attachment to the filling spout of an automobile radiator and provided with an open top surrounded by a concentric gasket, a cap hinged to the rear of said body and provided with a central opening for the reception of a motometer or the like ornament, said cap having formed integral therewith on opposite sides of said opening, two upstanding lugs provided with inclined surfaces and

forward stop abutments, said body having 20 in line with said lugs, housings arranged on opposite sides thereof and provided with vertically shiftable pivot pins, a bail provided with downward extensions pivotally mounted on said pins and having an upper 25 portion adapted to swing diametrically across said cap to engage the inclined surfaces of said opposed lugs, said bail including an intermediate bowed portion curved rearwardly whereby when said bail is pivoted rearwardly to these pivot pins, the curved portion will swing clear of the hinged connection between the radiator cap and the radiator body.

In testimony whereof, I affix my signature.

EDWARD H. ELLISON.
